WASHBASIN

Joseph L. Brack, Chicago, Ill., assignor to Pullman-Standard Car Manufacturing Company, Chicago, Ill., a corporation of Delaware

Application July 1, 1941, Serial No. 400,641

13 Claims. (Cl. 4—169)

Folding washbasins in railway passenger car room accommodations are very desirable because they are extremely convenient and when not in use can be moved out of the way to leave the floor area normally consumed by stationary washbasins available for use by the occupants. Experience has shown that the top of the washbasin is commonly used as a handy depository for articles of jewelry and the like when the basin is in use. Many people neglect to remove these articles before folding the basin into its out of the way position, and in this manner it frequently happens that valuables are lost or at least are deposited in the waste pipe from which recovery is made possible only through the services of a mechanic.

The present invention deals with a washbasin of the folding type which is supported in such a manner that it very easily can be removed from its support so simply that the room occupant himself can recover his lost articles. This mounting means is extremely simple and inexpensive, and at the same time the basin is firmly supported in a manner whereby it can be tilted from an operative horizontal position to a vertical inoperative position.

The above results are some of the objectives sought by the present inventor when he made his invention. They constitute the principal objects and advantages of the present invention, others of which will become apparent from the following description and the drawings, in which

Fig. 1 is a fragmentary perspective view of a washbasin in its closed inoperative position in the basin housing;

Fig. 2 is a fragmentary perspective view corresponding to Fig. 1 showing a preferred form of the invention with the basin removed from the housing;

Fig. 3 is a vertical sectional view through a portion of the basin housing showing in solid lines the basin in its closed position and in dotted lines the basin in its open position;

Fig. 4 is a fragmentary vertical sectional view corresponding to Fig. 3 but showing the washbasin in its open position;

Fig. 5 is a detailed perspective view of the release trigger employed in holding the basin in its housing;

Fig. 6 is a fragmentary vertical sectional view through the basin and housing indicating the manner in which the basin is grasped when it is being removed from the housing;

Fig. 7 is a fragmentary horizontal sectional

view through the basin and housing taken on the line 7—7 of Fig. 3;

Fig. 8 is an enlarged vertical sectional view through one side of the basin showing the mounting means for holding the basin in place on its support and taken on the line 8—8 of Fig. 3;

Fig. 9 is a fragmentary vertical sectional view through a basin and housing showing a modified form of mounting means for the basin;

Fig. 10 is a fragmentary vertical sectional view through the basin and housing showing the basin in its closed position;

Fig. 11 is an enlarged detail perspective view of a portion of the basin and housing showing the means for mounting the basin in place on the housing;

Fig. 12 is a fragmentary vertical sectional view through the basin and housing showing the position of the basin when it is to be removed from the housing.

Fig. 13 is a vertical sectional view taken on the line 13—13 of Fig. 10; and

Fig. 14 is a horizontal sectional view taken on the line 14—14 of Fig. 10.

Specific embodiments of the present invention are selected for the purpose of disclosure in compliance with section 4888 of the Revised Statutes. Obviously, many modifications may be made without departing from the scope of the present invention.

Referring now to Figs. 1 and 2, the invention is illustrated in conjunction with a housing or cabinet member generally indicated at 25, having a front wall 26, a pair of side walls 27 and 28, and a rear wall 29 (Fig. 3). The housing may be closed at its top and bottom if desired. As shown in Fig. 2, a recess 30 is provided in the front face 26 thereof, and a washbasin generally indicated at 31, is mounted in this recess and neatly closes the opening when the basin is in its closed position shown in Fig. 1. Directly above the basin 31 in the housing 25 is a shelf 32, and, as shown, above the shelf 32 is a mirror 33. The recess 30 is bounded by a pair of vertically extending side walls 34, a back wall 35, and a top wall 36. Between the back wall 35 of the recess 30 and the rear wall 29 of housing 25 are channel members 37 and 38 having outwardly projecting flanges 39 and 40, respectively. These flanges are secured to the back wall 29 of the housing 25, and the rear wall 35 of the recess 30 is secured to the channel members 37 and 38 along their faces 41 and 42, respectively.

Directly below the channel member 38 is a wall

43, the upper end of which is flanged at 44 and is secured to the channel member 38 along its lower face. The wall 43 along its lower edge is secured to a flange 45 of a Z bar, generally indicated at 46, and having a downwardly projecting flange 47 for securing the bar to the rear wall 29 of the housing 25. An angle bar, generally indicated at 48, has an upwardly extending flange 49 secured to the rear wall 29 of the housing 25 and a horizontal flange 50 secured to the web of the Z bar 46. Projecting below the wall 43 is a lower wall 51 secured along its upper edge to the upwardly extending flange 45 of the Z bar 46 and extending diagonally downwardly and rearwardly until it engages the rear wall 29 of the housing 24 as indicated at 52. This wall 51 forms the rear wall of a sump or chute, generally indicated at 53, the other walls of which comprise a pair of side walls 54 and a front wall 55. The side walls 54 and the front wall 55 converge toward the bottom of the chute, the front wall 55 having a portion 56 leading into the bottom horizontal portion 57 from which a discharge or waste pipe 58 projects in a downward direction. The lower horizontal wall 57 of the chute 53 is provided with an opening through which the waste passes into the pipe 58. A perforated plate 59 is supported near the bottom of the chute 53 and is adapted to catch solid articles which are discharged into the sump 53. The upper edge of the front wall 55 of the chute 53 is flanged at 60 which flange is held between horizontal flanges 61 and 62 of angle members 63 and 64 respectively. These angle members are provided with vertically extending flanges which are secured to the front wall 26 of the housing 25. A shield 65 is secured to the horizontal flange 62 of angle member 64, and this shield projects in a general horizontal direction from the front wall 26 of the housing 25 into the basin recess 30.

The basin 31 (Fig. 2) is supported within the recess 30 on the housing 25 in a manner presently to be described. Directly above the basin, when it is in its horizontal operative position shown in broken lines in Fig. 3, is a faucet unit generally indicated at 66 having hot and cold water spouts, one of which is shown at 67 in Fig. 3, and hot and cold water faucet levers 68 and 68' (Fig. 2) for operating valves generally indicated at 69 in Fig. 3. Suitable piping 70 projects downwardly from the faucet valves 69 in the space between the walls 43, 51 and 29, the wall 51 being recessed at 51' as best shown in Fig. 7. These pipes 70 are connected to some supply of water (not shown). Again referring to Fig. 2, a soap dish 71 forms a part of the faucet unit 66.

The basin 31 includes a pair of spaced vertical sides 72 and 73, a front vertical edge 74, and a rear edge 75. A bowl 76 is provided in the top face of the basin, and this bowl is surrounded by a basin top surface 77. The bowl 76 extends to the rear of the basin, as indicated in broken lines 78 in Fig. 2 below the top surface 77, and is provided with a lip 79 over which the contents of the basin are poured for emptying. A lower face 80 (Fig. 1) of the basin becomes the outer or front face thereof when the basin is in its closed position shown in Fig. 1 and is substantially flush with the front face 26 of the basin housing 25.

The preferred form of the present invention is shown in Figs. 2-8, inclusive. In this form, the basin on each of its vertical sides 72 and 73 is provided with a horizontal slot 81 opening at 82 at the rear edge of the basin.

Referring to Figs. 6 and 7, a channel member 83 provided with outwardly extending flanges 84 and 85 is secured to the inner face of each of the side walls 72 and 73 in such a manner that the channel straddles the slot 81. This channel member 83 extends from the extreme rear edge of the basin 31 as best shown in Fig. 6, parallel to the slot 81 and terminates short of the end 85 of the slot 81.

10 Fulcrumed to the channel member 83, at 86 (Fig. 6) is a trigger or release member 87 having an arm 88 extending from the fulcrum point 86 toward the top surface 77 of the basin and an arm 89 extending from the fulcrum point 86 in a direction normally substantially parallel to the upper surface 77 of the basin (Fig. 4). The rear face 75 of the basin is disposed diagonally as best shown in Fig. 3, and the arm 89 of the trigger member 87 normally projects beyond the rear face 75. A tension spring 90 secured at one end to an angle clip 91 fastened to the underneath face of the basin top 77 and to an ear 92 on the arm 89 of the trigger member 87 is normally under tension sufficient to hold the trigger member 87 in the position shown in Fig. 4. The free end of arm 88 is bent substantially at right angles to the arm to form a finger engaging portion 93. At the free end of arm 89 is locking member 94 having horizontal and vertical locking edges 95 and 96 respectively. As best shown in Figs. 5 and 7, the locking member 94 comprises a face 97 substantially at right angles to the arm 89 and a face 98 substantially parallel to the arm 89. The locking edges 95 and 96 are provided in the face 98 of the locking member 94. As shown in Fig. 7, the channel member 83 is slotted at 83' to receive a portion 98 of the trigger member 87. The fulcrum 86 in the form shown comprises a machine screw 99 (Figs. 4 and 7) passing through an opening 100 (Fig. 5) in the trigger member 87.

Referring to Figs. 2 and 7, on each of the vertical walls 34 of the recess 30 is a pivot support member 101 comprising a plate 102 secured to the vertical walls 34 and a lug 103 projecting outwardly from the plate 102. As best shown in Fig. 7, the lug 103 is adapted to pass through the slot 81 in the corresponding side of the basin 31, and when the basin is in its fully mounted position, shown for example in Fig. 4, the lug 103 is disposed at the extreme end 85 of the horizontal slot 81. The trigger member 87 normally is in the position shown in Fig. 4, and the vertical locking edge 96 holds the lug 103 in this slot.

When the basin is mounted with the lug 103 in its normal position in the slot 81, as shown in Figs. 3 and 4, the basin 31 can be moved from a horizontal operative position indicated in broken lines in Fig. 3 to a vertical inoperative position shown in solid lines. Thus, the basin is pivotally mounted and when not in use is rotated to its closed position so that it is entirely out of the way. As indicated in Fig. 1, 60 a hand grasp member 104 is provided on the underneath face 80 of the basin to facilitate the opening and closing of the basin. As shown in Fig. 3, a rubber bumper 105 is provided on the underneath face of the horizontal flange 44 of the wall 43, and when the basin is in its open position the extreme rear upper edge thereof engages this rubber bumper to hold the basin in this open position. Rubber bumper members 106 are provided on the inner face of wall 35 65 at the rear of the recess 30 and these bumpers 70 75

engage the basin top surface 77 when the basin is closed to serve as a stop for the basin. The wall 43 at the back of the recess 30 is spaced a sufficient distance from the axis of rotation of the basin through the lugs 103 so as to provide proper clearance for the rear edge of the basin during its pivoting movement.

When it is desired to remove the basin from its support, a hand indicated at 107, in Fig. 6, is placed at the rear edge adjacent to each of the sides 72 and 73 of the basin, and the fingers of each hand apply a force against the finger engaging portion 93 of the corresponding trigger member 87 and each trigger member is rotated in a clockwise direction, as shown in Fig. 6, about its respective fulcrum 86 so as to lower each of the locking members 94 with respect to its corresponding lug 103. Thus, the slot 81 is cleared of the obstructing locking member 94 and the basin 31 can be raised, during which time the slot 81 is drawn off the lug 103, the lug passing through the open side of the slot. In this manner, the basin is removed from its support, as shown in Fig. 2.

To return the basin to its support in the housing 25, it is held in its horizontal position shown in Fig. 2 and the slots 81 are aligned with respect to their respective lugs 103, and the basin is then moved into the recess 30 until the slots move into their respective lugs. The basin is continued to be moved into the recess 30 in a general horizontal direction. As can be seen from Figs. 5 and 6, the rear face of the locking member 94 is provided with an inclined edge 108, and as the lug 103 engages this inclined edge, it forces the locking member 94 out of its way. When each of the lugs 103 is at the extreme end 85 of its respective slot 81, the corresponding trigger member 87 is forced to its locking position shown in Fig. 4 by the force of the tension spring 90, and in this manner the lug 103 on each side of the basin is locked in its respective slot by the locking face 96. The upward movement of the trigger member 87 in response to the tension spring 90 is stopped by the locking face 95 on each of the trigger members.

A modified form of the present invention is shown in Figs. 9-14, inclusive. In this form, the basin 31 is provided with a horizontal slot 109 on each side thereof adjacent to this rear edge which cooperates with a lug generally indicated at 110 (Fig. 11) to hold the basin in place in the housing. A reinforcing plate 111 (Fig. 14) is secured to each side of the basin 31 and the slot 109 extends through this plate as well as through the side walls 72 or 73 of the basin, as the case may be. Projecting inwardly on the inner face of each of the reinforcing plates 111 are a pair of integral flanges 112 and 113, one on each side of the slot 109 and extending for the major portion of its length in a direction parallel to the slot 109 as best shown in Fig. 11. These flanges 112 and 113 throughout the greater portions have their lengths bounding the parallel sides of the slot 109. Toward the inner end of the slot 109 the flanges 112 and 113 diverge at 112' and 113', and then converge at 112'' and 113''. These flange portions or walls 112', 112'', 113', and 113'' surround the inner end 109' of slot 109, the slot itself having straight walls 109'' throughout this area surrounded by the flange, and the flange in this position being set back from the straight portions 109'' of the slot 109. As best shown in Figs. 10 and 11, the walls 112'' and 113'' are substan-

tially straight over the greater portions of their respective lengths.

As best shown in Fig. 11, the lug 110 projects from a plate 114 fastened to the inner face of each vertical side wall of the recess 30. The lug comprises the main body portion 115 of substantially uniform diameter throughout its length and has a cammed portion 116 at the extreme outer end of the lug. This cammed portion 116 has a width a (Fig. 11) substantially corresponding to the diameter of the main body portion 115 of the lug 110 and a length b considerably greater than the width a . Thus, the cammed portion 116 in a direction corresponding to one axis of the lug body portion 115 projects beyond the main circumference of the body portion. As best shown in Fig. 14, the body portion 115 of the lug 110 in length is somewhat greater than the distance from the inner face 114' of plate 114 to the inner face 111' of reinforcing plate 111, and the diameter of the main body portion 115 of the lug is slightly less than the width of slot 109. Thus, the main body portion 115 of the lug can be passed through the slot 109. Since the walls 112 and 113 (Fig. 11) bound the slot 109 with the inner faces of these flanges aligned with the wall of the slot, it is necessary that the smallest diameter a of the cammed portion 116 of lug 110 be slightly less than the distance between flanges 112 and 113. As shown, this dimension a corresponds to the diameter of the main body portion 115 of the lug. Thus, when the cammed portion 116 of the lug is disposed as shown in Fig. 11 with its longest dimension b parallel to the longitudinal axis of slot 109, the cammed portion 116 of the lug readily can be passed between the spaced walls 112 and 113, so that the lug and cammed portion thereof can pass readily through the slot 109 and between the walls 112 and 113 to the extreme rear edge 109' of the slot. With the lug 110 in this position in its respective slot (Fig. 10) the main body portion 115 of the lug closely fits between the walls of slot 109, as shown in Fig. 14, but the cammed portion 116 of the lug is free to move between the walls 112' and 113' (Fig. 10). The dimension b of the cammed portion 116 of the lug is slightly less than the distance between walls 112' and 113'' and walls 112'' and 113', and the walls 112' and 113' and the free end 116' of the cammed portion 116 all are arced in a manner to permit the free end of the cammed head of the lug to clear these walls during its limited rotat-

ing movement.

Referring to Fig. 9, the basin 31 is mounted on the cabinet or casing 25. The lugs 110 projecting inwardly on the opposite vertical faces of the recess 30 in the housing 25 are seated in their normal positions at the inner ends of their respective slots. The spaced flanges 112 and 113 together with the slot 109 form a track in which the lug 110 operates. As shown in solid lines in Fig. 9, the basin 31 is in its open position with the lug 110 in the enlarged portion of the track and seated against the face 113'' of this track. The free curved edge 116' of the cammed portion 116 of lug 110 is disposed closely adjacent to the curved wall 113', and any horizontal force applied to the basin 31 in an effort to withdraw the basin from the housing 25 is opposed by the reaction between the end 116' of the cammed head portion of lug 110 and the wall 113'. Thus, when the basin 31 is in its open position it is locked in place in the housing 25.

When the basin 31 is moved to its vertical closed position shown in Fig. 10, the slot 109 as-

sumes a vertical position and the lug 110 is disposed in the enlarged portion of the track with its cammed head 116 against the wall 112' of the track. Any force tending to remove the basin from its support is resisted by the reaction between the cam 110 and the walls 112' and 112''.

To remove the basin 31 from its support, it is first rotated to an inclined position shown in Fig. 12 until the lug 110 is disposed with respect to slot 109 with dimension *b* of the cammed head 116 of lug 110 parallel with the longitudinal axis of slot 109. The slots on both sides of the basin assume this position with respect to their cooperating lugs 110, and the basin 31 may now be raised in a direction parallel to the arrow 117 shown in Fig. 12, during which movement the slot 109 moves with respect to the lug 110 and is withdrawn from the lug. In this manner, the basin is freed from these lugs and is thus removed from its support. To replace the basin on its support, it is disposed in the same inclined position shown in Fig. 12 with respect to the lugs 110 and then the basin is lowered onto these lugs with the longitudinal axis of the slot 109 corresponding in direction to the dimension *b* of the cammed head 116 of lug 110. After the basin has been mounted in place it is free to be rotated from the horizontal operative position to a vertical inoperative position and is effectively locked in place by the cooperation between the lugs and their respective tracks and can be removed only when the basin assumes the inclined position shown in Fig. 12.

It is to be noted that when the basin 31 is open for use, there is practically no opening in the front face of the cabinet 25 below the basin. This is made possible by diagonally disposing the face 75 of the basin and properly locating the fulcrum axis of the basin.

I claim:

1. The combination of an upright cabinet having a recess in its front face, a removable washbasin supported in the recess, a lug on each of the vertical sides of the cabinet recess and projecting into the recess, means providing a cooperating slot on each side of the basin opening adjacent to the rear edge of the basin, each lug being adapted to project into its corresponding basin slot, and a releasable catch member on the basin adapted to engage the corresponding lug to hold the basin in the cabinet recess.

2. The combination of a cabinet having a recess in its front face, said recess having vertical sides, a removable washbasin supported in the recess, a lug on each of the vertical sides of the cabinet recess and projecting into the recess, means providing a cooperating slot on each side of the basin opening adjacent to the rear edge of the basin, each lug being adapted to project into its corresponding basin slot, and releasable means on the basin for locking each lug in its respective slot to hold the basin in the cabinet recess.

3. The combination of a washbasin, a support for the basin including spaced vertical members, one adjacent to each side of the basin, means providing a slot on each of the basin sides opening adjacent to the rear side of the basin and extending horizontally when the basin is in horizontal position, a lug on each of the vertical support members projecting into the corresponding basin slot, each slot being just sufficiently wide to receive its lug, and releasable means cooperating with a lug for locking the lug in its corresponding slot.

4. The combination of a folding washbasin, a support for the basin including spaced vertical members, one adjacent to each side of the basin, a track on each side of the basin which is horizontal when the basin is in horizontal position, each track being closed at its forward end and open adjacent to the rear side of the basin, a lug on each of the vertical support members on which the corresponding track is mounted, each lug normally assuming a position in its respective track at the forward end thereof, the basin being rotatable about the lugs to permit the basin to pivot from a vertical inoperative position to a horizontal operative position, each of the tracks being adapted to move linearly with respect to its lug so that the basin can be removed from the lugs, and releasable means cooperating with a lug for locking said lug in its track.

5. The combination of a washbasin, a support for the basin including spaced vertical members one adjacent to each of the basin sides, each of the vertical members and the adjacent side of the basin constituting cooperating faces, a track on one of the cooperating faces, a lug on the adjacent cooperating face adapted to engage said track, and a bearing portion at one end of the track, the other end of the track being open and the lug and the track being adapted to have relative movement therebetween in a direction linearly of the track so that disengagement between the track and the lug can be effected at the open end of the track, thereby permitting the basin to be removed from the support, said lug and track having releasable means cooperating therewith for locking the lug and the track relative to each other.

6. The combination of a washbasin, a support for the basin including spaced vertical members one adjacent to each of the basin sides, each of the vertical members and the adjacent side of the basin constituting cooperating faces, basin mounting means including a track on one of the cooperating faces and a lug on the adjacent cooperating face adapted to ride in said track, a bearing portion at one end of the track, the other end of the track being open, the lug and the track being adapted to have relative movement therebetween in a direction linearly of the track so that disengagement between the track and the lug can be effected at the open end of the track, thereby permitting the basin to be removed from the support, the lug including a cam portion adjacent to its outer end, the cam portion projecting radially from the lug to increase the width of the lug with respect to one axis at its outer end, the said bearing portion being circular and having a diameter greater than the greatest dimension of the cam portion, the remainder of the track having a width less than the greatest dimension of the cam portion and greater than the smallest radial dimension of the lug, the lug and track being relatively rotatable at the bearing portion and being linearly relatively movable at the narrow portion of the track only when the lug is disposed with its longest dimension directed linearly with respect to the track.

7. The combination of an upright cabinet having a relatively flat vertical face provided with a recess opening through said face, a basin adapted to fit into the recess, means providing a slot on each side of the basin adjacent to the rear edge of the basin, a lug on each side of the recess adapted to fit into the corresponding slot on the basin and about which the basin is adapted to

pivot from a vertical inoperative position inside the recess with the bottom face of the basin disposed substantially flush with the said flat face of the cabinet to a horizontal operative position projecting from the recess, each slot being open at its rear edge so that the corresponding lug may enter the slot, said lug and slot having means cooperating therewith for locking the lug in the slot to prevent linear movement of the lug relative to the slot and for releasing the slot for disengagement from the lug.

8. The combination of an upright cabinet having a relatively straight, flat vertical face with a recess opening through said face, a basin adapted to fit into the recess and to pivot from a vertical inoperative position in the recess to a horizontal operative position projecting from the recess, means providing a slot on each side of the basin adjacent to the rear edge of the basin, each of said slots being open at its rear edge and extending toward the front of the basin in a direction substantially parallel to the general plane of the basin and forming a bearing at the end of the slot nearest the front edge of the basin, the slot being bounded by substantially parallel edges extending from the open side to the bearing, the bearing being of a diameter greater than the distance between the parallel edges of the slot, a lug on each side of the recess adapted to fit into the corresponding slot on the basin and having one portion thereof with a diameter slightly less than the distance between the parallel edges of the slot and another portion with a diameter greater than the distance between the parallel edges of the slot but slightly less than the diameter of the bearing, the narrow portion of each lug being adapted to be passed through the open end of the corresponding slot and into the bearing, the bearing being rotatable relatively to the portion of the lug having the larger diameter and the parallel edges of the slot being adapted to cooperate with the lug to lock the lug to prevent linear movement thereof relative to the slot.

9. The combination of a washbasin, a support for the basin including spaced vertical members one adjacent to each of the basin sides, each of the vertical members and the adjacent side of the basin constituting cooperating faces, a track on one of the cooperating faces, a lug on the other cooperating face adapted to engage said track, a bearing portion at one end of the track, the other end of the track being open, the lug and the track being adapted to have relative movement therebetween in a direction linearly of the track so that disengagement between the track and the lug can be effected at the open end of the track, a locking member movably mounted on the cooperating face having the track and adapted to obstruct the path of the lug toward the open end of the track so as to lock the track relatively to the lug, and means accessible from the front of the basin for moving the locking member out of obstructing relation to the lug.

10. The combination of an upright cabinet having a recess in its front face, a removable washbasin member normally supported in the recess and having a slot open to the rear formed in each side of the member, a lug on each of the vertical sides of the recess projecting into the recess, a catch on each side of the washbasin member normally engaging one of the lugs so as to mount said member in the recess, and means mounting the catch for pivotal movement out

of engagement with said lug whereby the washbasin member may be removed from the support by causing the slot to move relatively to the lug until the open end of the slot passes the lug.

- 5 11. The combination of an upright cabinet having a recess in its front face, a removable washbasin normally supported in the recess and having a bearing member on each of its sides, a lug on each of the vertical sides of the recess projecting into the recess, said bearing members each having a slot opening to its rear, a catch on each bearing member normally engaging one of the lugs so as to mount the washbasin in the recess, and means mounting the catch for pivotal movement out of engagement with said lug whereby the washbasin may be removed from the support by causing the bearing member to move relatively to the lug until the open end of the slot passes the lug.
- 10 12. The combination of a cabinet having a vertical front face and having a recess in the cabinet opening through said front face, a basin adapted to fit in said recess and having a flat bottom face, a pair of lugs in the recess positioned one on each side of said recess and projecting into the recess in a direction parallel to the front face of the cabinet, and means providing a slot on each side of the basin adjacent to the rear face thereof, the slots being disposed substantially parallel to the top of the basin and having an opening at the rear of the basin and a bearing portion at the opposite end thereof, the basin normally being pivotally mounted on the lugs with each lug disposed in the bearing portion of the corresponding slot so that the basin can be moved from a horizontal operative position to a vertical inoperative position in the recess with the bottom face disposed substantially flush with the front face of the cabinet in said latter position, each of said lugs and slots having means cooperating therewith for locking the lugs and slots relative to each other and for releasing the slots for disengagement from the lugs.

- 15 13. The combination of a cabinet having a vertical front face and having a recess in the cabinet opening through said front face, a basin adapted to fit in said recess and having a flat bottom face, a pair of lugs in the recess positioned one on each side of said recess and projecting into the recess in a direction parallel to the front face of the cabinet, means providing a slot on each side of the basin adjacent to the rear face thereof, the slots being disposed substantially parallel to the top of the basin and having an opening at the rear of the basin and a bearing portion at the opposite end thereof, the basin normally being pivotally mounted on the lugs with each lug disposed in the bearing portion of the corresponding slot so that the basin can be moved from a horizontal operative position to a vertical inoperative position in the recess with the bottom face disposed substantially flush with the front face of the cabinet in said latter position, an arm pivoted to the basin on each side thereof, and a locking member on each arm adapted to cooperate with its corresponding lug so as to lock the lug relative to the slot to prevent linear movement therebetween, the arm being accessible from in front of the basin and being adapted when rotated to move the locking member away from the lug so as to permit linear movement of the slot relative to the lug.

JOSEPH L. BRACK.

CERTIFICATE OF CORRECTION.

Patent No. 2,315,927.

April 6, 1943.

JOSEPH L. BRACK.

It is hereby certified that error appears in the printed specification of the above numbered patent requiring correction as follows: Page 5, first column, line 63, claim 9, for "the front" read --in front--; and that the said Letters Patent should be read with this correction therein that the same may conform to the record of the case in the Patent Office.

Signed and sealed this 25th day of May, A. D. 1943.

(Seal)

Henry Van Arsdale,
Acting Commissioner of Patents.
